UNITED STATES PATENT OFFICE.

IRA M. DAVIDSON, OF LOS ANGELES, CALIFORNIA, ASSIGNOR, BY DIRECT AND MESNE ASSIGNMENTS, OF ONE-THIRD TO GEORGE H. SHAW AND ONE-THIRD TO NORMAN L. PHILP, BOTH OF LOS ANGELES, CALIFORNIA.

ROTATING MOTOR.

1,219,877.

Specification of Letters Patent. Patented Mar. 13, 1917.

Application filed July 7, 1915. Serial No. 38,616.

To all whom it may concern:

Be it known that I, IRA M. DAVIDSON, a citizen of the United States, residing at Los Angeles, in the county of Los Angeles 5 and State of California, have invented a new and useful Rotating Motor, of which the following is a specification.

An object of the invention is to provide a multi-cylinder, compound drive constant 10 speed rotating motor adapted for internal combustion, electric, steam or other power applied through relatively small units in combination with each other to produce any required power through a multiplicity of 15 impulses made effective to drive a shaft or other power transmitter.

This invention relates to a motor capable of utilizing mechanical energy from internal combustion, from steam, and from electricity; and is designed to apply such energy 20 with maximum torque exerted upon a power shaft from multiple units of minimized size.

The invention is designed to be particularly 25 advantageous in the use of power generated by internal combustion of gas or carbureted air, and the description herein will set forth the construction and operation of the invention as applied for utilizing energy 30 from internal combustion and will serve to indicate the mode of its application for the utilization of energy from steam and electricity.

An object of the invention is to provide 35 a highly effective motor, the balance of which relative to the power shaft driven by said motor will not be disturbed by the operation of the motor, thus adapting the motor in a highly advantageous manner to 40 use for driving the propellers of air craft.

Another object of the invention is to maximize the efficiency of the motor, and incidentally minimize the noise of operation, by providing a housing to encircle the 45 power units and receive the exhaust of internal combustion or steam engines as it issues from the internal combustion chambers or from the steam cylinders, as the case may be, of such engines.

50 Other objects are to provide a superior combination of a multiplicity of energy units to communicate power to a single shaft; exact timing of said units through the medium of a minimum number of parts;

minimized electric connection and simple 55 construction of means for igniting the charges in the internal combustion chambers; and simplicity of means for securing exact sequence of impulses from a multiplicity of units.

60 Other objects are cheapness, simplicity, rigidity and strength combined with lightness, ease of assembling and taking apart, compactness and convenience of mounting.

A further object is to make provision 65 whereby the motor may form the connection between its support and a driving member in movable relation to said support.

The invention is constructed to employ 70 the inertia of the engine cylinders, pistons, piston rods, and crank shafts to increase the efficiency, certainty and steadiness of operation and the motor is constructed with its power cylinders and pistons arranged in parallelism with the power shaft and its 75 crank shafts radially arranged relative to the power shaft, thereby maintaining a maximized equilibrium.

The accompanying drawings illustrate 80 the invention as applied in the construction of a seven-cylinder internal combustion rotating motor adapted to exert twenty-eight impulses upon the power shaft at each revolution; and indicates that form of embodiment which I at present deem most satisfactory and effective for use with units of the internal combustion type.

85 Figure 1 is a plan, partly in section and viewed from irregular line x' , Fig. 2, of a rotating motor constructed in accordance 90 with this invention and arranged for application to automobiles, aeroplanes and motor boats; and for producing power for driving machinery of all kinds. Only two cylinders are indicated the other cylinders 95 that might appear from the nature of the view being omitted to avoid confusion of lines.

95 Fig. 2 is an end elevation, partly in section and viewed from irregular line x^2 , 100 Fig. 1. Parts are broken away to show parts otherwise hidden.

105 Fig. 3 is an elevation analogous to Fig. 2, being partly in section on line x^3 , Fig. 1. The engine is shown with unit No. 1 in ignition position, the same being slightly behind the position shown in Fig. 2.

Fig. 4 is a broken axial section showing

a cylinder and crank case and attached parts on line x^4 , Figs. 1 and 2. A piston partly broken away for clearness of illustration is also shown, and the parts are in the 5 position occupied at the moment of final exhaust and initial intake.

Fig. 5 is a cross section on line x^5 , Fig. 3, illustrating the ignition means.

Figs. 6, 7, 8, 9, 10, 11 and 12 are diagrammatic views illustrating the firing sequence 10 of the respective units during one quarter turn of the power shaft. The firing position of each unit is indicated by heavy circles. Curved feathered arrows indicate 15 the direction of revolution.

Arrows on the various section lines indicate the direction of sight.

In Figs. 2 and 3 the insulating bus-bar support is mottled to allow the dotted lines 20 of concealed parts to show clearly.

In the combination constituting an internal combustion engine constructed in accordance with this invention, a set of internal combustion cylinders and a set of ignition 25 devices are involved; one set being of an even number and the other set being of an odd number. For convenience of illustration the motor is shown as constructed with a set of seven cylinders 1, 2, 3, 4, 5, 6, 7 and 30 a set of ignition points a , b , c , d ; and the sequence of firing is 1, 6, 4, 2, 7, 5, 3. The firing of this sequence occurs during each quarter of a revolution, thus making twenty-eight impulses for one full revolution. The 35 ignition points a , b , c , d are relatively stationary points of electrical distribution and the ignition occurs when the spark plugs pass such points.

The motor comprises a shaft 8; two frames 40 9, 10, in journaled and fixed relations respectively to the shaft and relatively revoluble with respect to each other; power units 11; a bevel gear 12; said bevel gear on the one hand, and power units on the other hand being fixed to the frames 9 and 10 respectively; and power-transmitting means 45 13 connecting the motor units 11 with the bevel gear 12 to cause relative rotation between the shaft and one of the frames when the motor units are operated.

Each motor unit may comprise a cylinder; as for instance, the cylinder 7; a piston head 14, and an ignition device 15.

The power-transmitting means connecting 55 said motor unit with the bevel gear 12 may be a connecting rod 16, a pin 17 connecting said connecting rod with the piston head 14; a crank shaft comprising the journals 18, 19, crank 20 with wrist-pin 21, a pinion seat 22 and a reduced end bearing 23. Said power-transmitting means also comprises a pinion 60 on the pinion seat 22; and a journal bearing 25 on the frame 10 adjacent the bevel gear 12. Said bevel gear 12 in the construction 65 shown is a bevel crown wheel fixed by

bolts 26 to a standard 27 having flanges 28 bolted to the angle-iron body 29 of the frame 9 and forming a journal bearing for the shaft 8. Said frame 9 is provided opposite the standard 27 with an anti-friction journal bearing 30 that supports a part of the shaft 8 and allows it to rotate relative to the frame 9. Said frame 9 is constructed to constitute the base of the motor and with this object in view is shown as provided with trunnions 31. 70

Said trunnions are adapted to be mounted in journal bearings, not shown, on the chassis or frame of the machine to be driven, thus leaving the shaft free to be attached to a driven part, such as the axle of an automobile that is in movable relation to said chassis, so that the support of the motor is what may be termed a two-point support allowing direct connection to the axle or other driven part. 75

The internal combustion engine is of the two-cycle type, the explosive mixture or carbureted air being taken in through the carburetor 32 and conducted through a hollow section 33 of the power-shaft 8 which, with its connections, serves as a manifold, having hollow radial arms 39 communicating through ports 40 with the compression chamber 41 formed by the crank case 42 from which the carbureted air passes through channel 43 and port 44 into the combustion chamber 45, being directed by the deflector 46 onward through the ignition end of the internal combustion chamber where it is returned to the inlet end of the cylinder which is provided with the exhaust port 47 that opens outwardly away from the shaft 8 or axis of revolution of the engine cylinders. 85

Guard means 49 and 49' are fixed to the frames 9 and 10 respectively within the circle of abutments and surrounding the circle of power units, said guard 49 being provided with open ports 50, each extending therein for a distance corresponding to the period during which the exhaust port 47 90 may be opened by its piston; thus to admit the exhaust to said exhaust port 50. The guard 49 constitutes the inner wall of a hollow housing 51 in which the expanded exhaust, if any is conducted to the final exhaust port 51' and the guard 49' is preferably formed by an annularly bent plate positioned with a close working fit adjacent or against said inner wall 49 of the exhaust chamber and having apertures 49'' encircling and being suitably secured to and revolving with the various cylinders. Studs 8 extending through the guard-plate and into the cylinders adjacent the exhaust port fix the guard-plate to the cylinders. See Fig. 1. 95 By this arrangement the guard means 49 and 49' are revoluble relative to one another, the guard means 49' serving as a port cover for that portion of each port 50 not in communication with an exhaust port 47, thus to 100 105 110 115 120 125 130

prevent leakage of the exhaust while the exhaust ports 47 are passing the ports 50.

5 Tangential abutments 48 are arranged opposite the respective ports 50 of the housing, which abutments extend obliquely away from the circular path of the revolving power units to deflect the exhaust gases and cause a circulation within the housing, which circulation produces a vortex action 10 upon the entering exhaust to thereby decrease back pressure.

In practice the engine may be started by revolving the power units and the power shaft to cause the charges of carbureted air 15 or other fuel mixture to be sucked in through the carbureter 32, the hollow section 33 of the shaft and the manifold arms 39, into the chamber 41 of the crank case 42, from which the charge in a more or less compressed condition is forced into the combustion chamber of the cylinder. Upon such 20 ignition in a cylinder, an impulse is given to the piston 14 thereof driving the piston to the position shown at Fig. 1; whereupon the 25 products of combustion exhaust through the ports 47 and 50 onto the abutment 48 and around the hollow housing 51.

Power is thus applied through the crank shaft and the connections or train 13, 12 as 30 above stated, to drive the power shaft 8 and the gear ratio between the gear 12 and pinions 24 is preferably 4 to 1 so that when used in connection with four ignition points 35 each cylinder receives an impulse for every quarter revolution of the power shaft or four impulses per revolution, irrespective of the number of cylinders used, provided this number is uneven so that no two impulses occur simultaneously. As clearly appears from the 40 above sequence, there will result, in case of a construction and arrangement of seven power units and four ignition points as shown, no less than twenty-eight rapidly succeeding explosions during the first revolution of the series of internal combustion 45 units and the shaft, and at each succeeding revolution thereof. The number of impulses given to the power shaft at each revolution will equal the product of the number of power units multiplied by the number of 50 ignition points.

The frame 10 may be constructed in any suitable way, but I deem it especially advantageous to construct it in the manner which 55 I shall now detail.

Three steel plates 53, 54, 55 are connected to the power units 1, 2, 3, 4, 5, 6, 7; this being conveniently done by making holes 56, 57 and 58 through the plates 53, 54, 55 respectively 60 to fit respectively the stud 59 extending from the end of the crank case to fit the body of the cylinder and to fit the spark plug 60 of the ignition device, so that the cylinders are held in perfectly true relation to each other, 65 the plate 54 being securely bolted by bolts 61

to a hub 62 that is fixed by suitable means such as set screws 63 to the solid section 64 of the power shaft 8; the plate 55 being fixed by rivets 65 to a hub 66 on the hollow section 33 of said power shaft 8, which hollow section 33 is closed by the solid section 67 that is screwed thereinto, and that is carried by the anti-friction journal bearing 30. 70

The plate 53 is provided with anti-friction means 68 to allow said plate to rotate relative to the journal bearing 27 and an annular frame wall 69 is positioned between and fixed to the frame plates 53, 54, by any suitable means, as by screws 70, to form a lubricating chamber 71 in which the pinions 80 24 are arranged to run, said chamber being filled with lubricant to thus properly lubricate the working parts.

The ignition points *a*, *b*, *c* and *d* are arranged in a circular path coinciding with the circular path of the ignition devices 15 and are suitably supported from the stationary frame 9 as by means of an annular insulation bar 72 that is carried by clips 73. 85

Said ignition points are electrically connected with the spark coil 52 through an electrical circuit 74, see Fig. 3, and each comprises a terminal piece 75 suitably positioned in place upon the under-side of the bar and connected with the circuit leads by wing nuts 90 76, the ignition occurring by jump spark as the spark plug 60 passes under the terminal pieces 75.

The hollow shaft section 33 is provided with inlet ports 77 around which is mounted 100 a chambered stuffing-box 78 to which is connected the carbureter 32. Said carbureter being non-rotatably supported relative to the shaft 8 by an arm 79 extending from the frame 9 and attached to the carbureter. 105

The invention may be embodied in various forms and it is understood that I do not contemplate limiting myself to the specific form shown and described.

It is very desirable that the impulses shall 110 be in succession and that no two impulses be given at the same time; and in order to effect this result I have discovered that it is necessary that the number of cylinders shall be odd and the number of ignition points to 115 energize the spark plugs or ignition devices of said cylinders shall be even; the cylinders being spaced equally apart and the relatively stationary ignition points also being spaced equally apart.

This relation remains true with a two-cycle engine, but if a 4-cycle engine were to be used the arrangement for ignition will have to be of a different character according to the number of cylinders, but it still remains necessary that the number of cylinders shall be odd in either type of engine. 125

I claim:—

1. A motor comprising a frame, a power shaft journaled to said frame, a bevel-wheel 130

- fixed to said frame, crank shafts radial to said power shaft, pinions on the crank shafts meshing with said bevel-wheel, cylinders arranged in parallelism with said power shaft 5 and having exhaust ports opening outwardly from the shaft, pistons in said cylinders and connected to drive said crank shafts to turn the power shaft, means to supply expansive medium in the cylinders to drive said pistons, and a hollow housing rigidly mounted in the frame and encircling the cylinders and provided with ports adapted to register with said exhaust ports to thus receive the exhaust from the cylinders.
- 10 2. A motor comprising a frame, a power shaft journaled to said frame, a bevel-wheel fixed to said frame, crank shafts radial to said power shaft, pinions on the crank shafts meshing with said bevel-wheel, cylinders ar-

ranged in parallelism with said power shaft 20 and having exhaust ports opening outwardly from the shaft, pistons in said cylinders and connected to drive said crank shafts to turn the power shaft, means to supply expansive medium in the cylinders to drive said pistons, a hollow housing encircling the cylinders and provided with ports adapted to register with said exhaust ports to receive the exhaust from the cylinders, and an annular guard on the cylinders adjacent said housing to cover the housing ports when said ports are not in communication with the exhaust ports to thus prevent leakage through said housing ports.

In testimony whereof, I have hereunto 35 set my hand at Los Angeles, California. This 2nd day of July, 1915.

IRAM DAVIDSON.
